VEGETABLE COOLING SPRAY

Jakob V. C. T. Christensen, Jr., Sierra Madre, Calif., assignor to Cecile W. Christensen, Los Angeles, Calif.

Application September 13, 1933, Serial No. 689,244

6 Claims. (Cl. 299—58)

The present invention relates generally to spray devices, and more particularly to those used to send out a very fine spray of water to wet and cool vegetables on a display stand. Devices of this character are generally placed centrally of the display stand, and usually comprise a nozzle emitting a very fine stream of water and a dispersing surface upon which the stream impinges. Upon striking this surface, the stream of water is broken up into minute drops which spread out over the stand and settle upon the vegetables.

A difficulty encountered in former devices where a flat, horizontal surface is provided for the vertically moving stream to strike against, is that a portion of the stream is broken up into drops so fine as to form a cloud or mist that, instead of quickly settling onto the vegetables, remains suspended in the air for a short time and is easily blown away by air currents. This not only fails to cool the vegetables, but is objectionable to persons nearby. A large part of the rest of the water collects in large drops that fall in one place and so are not beneficially distributed. Also, in prior devices where the dispersing surface is of limited extent, it may not be accurately aligned with the water stream so as to give the best spray results; and the rigidity of the parts makes difficult any adjusting movement of the surface.

It thus becomes a general object of my invention to provide a device that breaks up the entire water stream into a downwardly directed spray, causing it to settle quickly upon the vegetables and yet spread evenly over a large area. Such a spray keeps the vegetables uniformly cool.

Another object of the invention is to provide a means for properly positioning the dispersing surface, so that the surface and the nozzle can easily be aligned after installation to secure the desired results.

In a device characteristic of my invention, I provide a dispersing member having an indented dispersing surface against which the water stream strikes, and by virtue of the shape of the surface is prevented from becoming too widely diffused in the surrounding air. I also provide a flange about and spaced above the dispersing surface. This flange cooperates with the inwardly curved surface to direct the spray downwardly as well as outwardly so that the water settles quickly onto the vegetables.

This dispersing member is supported by a frame member made of pliant material which can be relatively easily bent to bring the curved surface into proper vertical alignment with the nozzle to have the water stream strike at the proper

point. As an additional means of securing adjustability, I preferably mount the dispersing member for movement toward and away from the nozzle.

How the above and other objects and advantages of my invention are attained will be more readily understood by reference to the following description and the annexed drawing wherein I describe and illustrate a present preferred embodiment of my invention.

In the drawing:

Fig. 1 is a side elevation of a spray device constructed in accord with my invention;

Fig. 2 is an enlarged section on line 2—2 of Fig. 1 but showing a double-ended dispersing pin; 15

Fig. 3 is an enlarged section on line 3—3 of Fig. 1;

Fig. 4 is a fragmentary elevation, partially in section, of a variational form; and

Fig. 5 is a fragmentary elevation of a gang of 20 sprays.

In the preferred embodiment of my invention illustrated in Figs. 1 to 3, the spray comprises a cap 10 attached to water supply pipe 12 by means of an adapter 14 which accommodates 25 various threads and sizes of water supply pipe as will be understood. On top of cap 10 is nozzle 15 threaded or pressed into the cap and provided with a longitudinal bore 16 through which the jet of water issues. Wings 13 are formed on cap 10 so that cap may be turned down like a thumbscrew. To strain out impurities that might tend to close bore 16, there is provided a fine wire screen 18 held between a pair of washers 19, 20 within the body of the cap. Adapter 14 is 35 screw-threaded into cap 10 and holds the screen and washer assembly in place as illustrated in Fig. 3.

Integral with cap 10, is frame member 22 having at its upper end a horizontally extending portion formed at its extremity with disc 24. The dispersing member, here in the form of pin 28, is preferably threaded into the end of frame member 22 to be supported thereby and passes centrally of disc 24. Disc 24 acts as a shield to stop 45 the stream of water should it not initially strike the end of pin 28.

As illustrated best in Fig. 2, the lower end of pin 28 is indented to form a concave surface 30 against which the water stream hits. Since an 50 even distribution of water in all directions is desired, the end of pin 28 is circular in cross section, though any other shape might be used if desired. A short distance above its end, pin 28 is formed with an annular shoulder or flange 32 55.

of sufficiently greater radius than the end of the pin to overhang or project beyond surface 30 about its entire circumference. Pin 28 in Fig. 2 is the same as in Fig. 1, except that the top end 5 of the pin is provided with a dispersing surface 30a of different contour than and interchangeable with surface 30 by reversing the pin.

Frame 22 is made of some pliant material, by 10 which is meant that it is made of a substance possessing sufficient rigidity to remain securely in adjusted position but which is, at the same time, relatively easily bent so that pin 28 may be moved into proper alinement with nozzle 15. Manufacturing cost may be materially reduced if 15 it is not necessary that the several operations insure accurate alinement between the bore of nozzle 15 and dispersing surface on pin 28, but that after installation, member 22 may be slightly bent or twisted to accurately aline the dispersing 20 pin.

In the case of a single spray device as illustrated here, frame 22 will generally be integral with or supported by cap 10; but where a series 25 of such spraying devices are formed, as in Fig. 5, by a series of nozzles in a pipe, frame members 22 may be supported from another member, such as bar 25, in which case installation is made simpler if the frame member itself may be bent to secure proper alinement. Accurate alinement of 30 bore 16 in nozzle 15 and pin 28 will be seen to be necessary since the end of pin 28 is of not large extent, and particularly because the jet of water issuing from bore 16 should strike centrally of concave surface 30 in order to be evenly distributed in all directions. Further adjustment 35 of the position of surface 30 is had by turning pin 28 to move the pin longitudinally relative to its support. This aids easy alinement, and changes the distance between the pin and nozzle 40 to change the spray. Reversing or changing pins to change surface 30 is also made very simple. However, the dispersing surface might be rigidly attached to the frame support 22 if adjustment is not desired.

Upon striking pin 28, the stream of water is entirely broken up into minute droplets, but the concave nature of surface 30 so confines the spray and directs the air currents that these droplets are forced downwardly as well as outwardly from 50 surface 30, forming a definite downwardly directed conical spray, and so settle upon the vegetables rather than drift away. Within limits, decreasing the radius of curvature of surface 30, which is preferably spherical, tends to accentuate 55 this down-draft effect; however, it is not intended to limit the invention to spherical surfaces 30 and 30a, for it will be understood that a hollowed or indented surface having any contour desired may be used. In this connection, the expression 60 concave as applied to surface 30 contemplates any equivalent indented surface. Restricting the area of the dispersing surface, and concaving it, cause the water stream to be completely broken up, without opportunity for part of the mist to coalesce into large drops that drip off the dispersing 65 surface, as is the case when the stream strikes a flat surface of relatively larger area. As illustrated in Figs. 2 and 3, which are to the same scale, the concave impact or dispersing surface 70 30 is restricted to a diameter substantially eight times the diameter of the relatively fine discharge orifice 16, a ratio of substantially eight to one between these diameters giving proper and typical performance according to the invention, and 75 being characteristic thereof. This ratio may be

slightly increased without vitiating the results characteristic of the present invention, but a substantial departure from the ratio given will be found in practice to result in loss of the described definite spray cone and dripless impact pin. It 5 is important to note that the lower end of the impact pin, adjacent the concave end surface, is smooth sided, and that the concave end surface is of the full diameter of the pin end, so as to intersect the smooth side surface of the pin and 10 form a continuous sharp edge 31 (Fig. 2), which in the form shown is circular. This sharp edge 15 31 is found in practice to be essential to the results herein described, and if it accidentally becomes nicked or mutilated in any way the uniform downwardly directed spray cone is lost, and large drops of water drip from the pin. I accordingly find it necessary to protect this sharp edge after manufacture of the pin, and always pack the assembled device for shipping with a 20 rubber protecting tube slipped on over the pin end.

Although my improved spray will operate without, it is preferred to use flange 32 which acts as a deflector for the upwardly moving air carried 25 by the water stream. Thus shoulder 32 aids the downward movement of air currents carrying the finely divided water spray onto the vegetables below the device, and helps prevent coalescence 30 of the mist particles. It is preferable that flange 32 be placed slightly above surface 30, i. e., spaced from the surface in the direction of stream flow from nozzle 15.

A simplified form of the spray is shown in Fig. 4, wherein frame member 22 supports shield 24, 35 and the shield is provided with an integral pin or boss 35 having its lower surface concaved at 30b to form a dispersing surface against which the stream of water strikes. The lower surface of shield 24 acts as a deflecting shoulder to turn 40 the air currents downwardly, and flange 32 is omitted. As described before, frame 22 is pliable so that surface 30b may be properly alined with the stream issuing from nozzle 15.

Having described certain typical forms of my 45 invention, it will be understood that changes in form and construction will readily appear to those skilled in the art without departing from the spirit of my invention, so that the appended claims are to be considered as illustrative of rather than 50 restrictive upon my invention.

I claim:

1. In a liquid spray device having a nozzle adapted to discharge a needle-like stream of water, a pin member mounted in line with said nozzle, said pin member presenting toward the nozzle a smooth-sided end portion having a concave impact end surface which intersects the smooth side surfaces of the pin end in a continuous unbroken sharp edge, the diameter of said pin end and concave impact surface being relatively small but being larger than the water stream impinging thereon, said impact surface deflecting the stream of water and forming a conical spray directed back towards the nozzle. 65

2. In a liquid spray device having a nozzle adapted to discharge a needle-like stream of water, a pin member mounted in line with said nozzle, said pin member having a smooth-sided end portion, of diameter substantially eight times the diameter of the nozzle orifice, said end portion having a concave impact end surface, of diameter larger than the water stream impinging thereon, which concave surface intersects the smooth side surfaces of the pin end in a continu- 75

ous unbroken sharp edge, said impact surface deflecting the stream of water and forming a conical spray directed back towards the nozzle.

3. In a liquid spray device having a nozzle 5 adapted to discharge a needle-like stream of water, a pin member mounted in line with said nozzle, said pin member presenting toward the nozzle a smooth-sided end portion having a concave impact end surface which intersects the 10 smooth side surfaces of the pin end in a continuous unbroken sharp edge, the diameter of said pin end and concave impact surface being relatively small but being larger than the water stream impinging thereon, said impact surface 15 deflecting the stream of water and forming a conical spray directed back towards the nozzle, and a single deformable arm supporting said pin member, said arm being adapted to be easily bent in any direction to aline the impact surface 20 with the stream of water or to vary the direction of the spray cone.

4. In a liquid spray device having a nozzle adapted to discharge a needle-like stream of water, a pin member mounted on line with said nozzle, said pin member presenting toward the nozzle a smooth-sided end portion having a concave impact end surface which intersects the smooth side surfaces of the pin end in a continuous unbroken sharp edge, the diameter of said 25 pin end and concave impact surface being relatively small but being larger than the water stream impinging thereon, said impact surface deflecting the stream of water and forming a conical spray directed back towards the nozzle, 30 and a flange on the pin end spaced a relatively short distance from the impact surface.

5. In a liquid spray device having a nozzle adapted to discharge a needle-like stream of water, an impact member mounted in line with said nozzle, said impact member presenting toward the nozzle a circular indented impact surface of relatively small diameter but larger than the diameter of the water stream impinging thereon, said indented impact surface being bounded by a continuous unbroken sharp edge 5 formed by the intersection of said impact surface with a smooth circular bounding surface which is substantially parallel to the direction of the water stream impinging on the impact surface, said impact surface deflecting the water stream and forming a conical spray directed back 10 towards the nozzle.

6. A spraying device comprising a single substantially U-shaped bracket arm, the end of one leg thereof being provided with means for threadedly receiving a liquid supply conduit and also 20 with a nozzle disposed in alignment with the liquid supply conduit, the end of the other leg of said U-shaped bracket being provided with a fixed splash plate of substantial area having a central threaded opening, a threaded deflecting plug of 25 relatively small diameter adjustably positioned in the threaded opening of said plate, said plug and nozzle being arranged in direct alignment whereby the point of deflection of the spray may be adjusted, the portion of said U-shaped bracket arm 30 opposite the entire range of adjustment of said plug being disposed sufficiently remote from the plug to prevent any substantial obstruction of the spray.
